UNITED STATES PATENT OFFICE.

HENRY RAUCH, OF MOUNT VERNON, NEW YORK.

CASK-PITCHING MACHINE.

933,202.

Specification of Letters Patent. Patented Sept. 7, 1909.

Application filed February 21, 1908. Serial No. 417,072.

To all whom it may concern:

Be it known that I, HENRY RAUCH, a citizen of the United States, and a resident of Mount Vernon, in the county of Westchester and State of New York, have invented certain new and useful Improvements in Cask-Pitching Machines, of which the following is a specification.

My invention relates to improvements in cask pitching machines, more particularly of the type which I have described in my United States Letters Patent No. 599,476, dated February 22, 1898, and also in a further United States Letters Patent No. 616,632, dated December 27, 1898. The apparatus described in the first of the said patents consists, briefly, of a kettle to receive the pitch arranged over a suitable furnace, and having below its bottom and preferably cast integrally with it one or more tanks to receive, through a valve-controlled inlet, pitch from the kettle. This tank, or each tank, if there be more than one, has an outlet-pipe, with a spray-nozzle on its upper end to deliver the pitch in the form of spray into the cask to be pitched which is supported on the cover of the kettle. The pitch is ejected from the tank by the admission over it of compressed air from some suitable source.

So far as above described, the apparatus is the same and operates the same as that described in my former patents. In operating such an apparatus, however, containing only the features above described, a difficulty is apt to arise, which it was the object of the second of the said patents to obviate. The difficulty referred to is that the molten pitch left in the kettle after the pitching operation, flows down into and fills the tank, and

when the apparatus cools this mass of pitch hardens; consequently, it is only by using great care and skill that the apparatus can be reheated without creating in the tank such an internal pressure as will explode the tank before the entire mass of pitch is melted sufficiently to allow the same to escape through the outlet pipes. This difficulty was sought to be obviated in the second of my above mentioned Letters Patent, by providing a relief device for the generated gases and vapors, so that they might escape prior to the melting of the entire mass of pitch and thus relieve the pressure in the interior of the tank. The said relief device consisted, as will be more fully seen by reference

to the said second patent, of a tube extending down nearly to the bottom of the pitch kettle, open at the bottom but adapted to be closed at the top when the apparatus was in use. A second tube, of such a diameter as to fit inside of the first mentioned tube, also open at the upper end but provided with a conical valve seat at the lower end was provided, and also a rod, the lower end of which was tapered into a conical form so as to serve as a valve. At the close of the day's operation of the machine, and while the pitch in the tank was still warm, the inner tube with its rod valve *in situ* was inserted into the first mentioned tube and secured. At the time of the next operation of the machine, the pitch having become cold and hard, the inner rod was detached from the adhesion of the cold pitch which had congealed about its lower end, and removed from the inner tube, thus leaving a free passage from almost the bottom of the tank into the open air, through which passage the generated gases and vapors formed by the heating of the pitch could escape. The fire was then started under the tank, and after the pitch in the lower part of the tank had become melted or softened it was possible to remove the inner tube, thus allowing a still larger and freer vent. When the heating and consequent softening of the pitch had progressed still further so that the same was liquid up to the lower ends of the pitch discharge pipes, so that there was no further danger of an explosion of the tank, a screw cap or other closure was applied to the upper end of the outer tube above described as forming part of the pressure relief mechanism.

The apparatus last above described has been found to generally work well in practice, but has not been entirely satisfactory owing not only to the adhesion of the cold pitch to the lower end of the rod or valve above described, but also owing to the fact that several operations were required both at the close of the use of the machine and also at the beginning of the next use, which operations required for their performance considerable care and skill.

The object of my present invention is to remove the difficulty above mentioned and to obviate the danger of any explosion of the pitch tank, and to provide means for the heating and liquefaction of the pitch, before

the lighting of the fire, to a sufficient degree to permit it to escape from the discharge pipes of the machine in case of any undue pressure from the generation of gas or otherwise, thus doing away with the necessity for an auxiliary relief device such as has been heretofore used in connection with machines of the type above described.

In the accompanying drawings Figure 1 10 is a vertical longitudinal section of a cask pitching machine constructed according to my invention, said section being taken on the line 1—1 of Fig. 2; Fig. 2 is a plan view of the same; and Fig. 3 is a detail view 15 showing in vertical section and on a larger scale a portion of the devices employed to soften the pitch in the lower part of the tank previous to lighting the fire under the tank.

A represents the kettle or reservoir set in 20 walls X over a furnace Y. This kettle has a cover A^x with a covered opening a therein for feeding in the pitch, a screen b to screen out foreign substances from the pitch, and one or more tanks B below the bottom c of 25 the kettle to receive a predetermined quantity of molten pitch, which latter flows down into the tank through a valve-controlled inlet d. The compressed air is admitted to the tank by pipes e, and the pitch is discharged 30 into the cask through an upright pipe f, having on its upper end a hose-nozzle g. All of the above is illustrated and fully described in my said former patent No. 599,476, and the operation in detail need not be 35 described here. It is sufficient to say that after the operation of the day is completed and the apparatus is allowed to cool off, the mass of pitch z in the tank B becomes hard.

The devices which are the subject of my 40 present invention will now be described.

Passing down through the cover A^x, the kettle or reservoir A, and the partition wall c which forms the bottom of the kettle A and separates it from the tanks B B, are 45 tubes 10, closed at their upper ends by caps 11 and provided near their upper ends with lateral escape cocks 12. The tubes 10 are open at their lower ends into the tanks B. Leading from some suitable steam generator 50 (not shown in the drawings) is a steam pipe 14, which passes downward into and through the tubes 10, forming loops 15 which extend nearly to the bottom of the tanks B and then return to the steam generator, or passage 55 into the open air, as circumstances may render desirable. Valves 16 of any suitable type are provided by means of which the passage of the steam into either or both of the said loops may be controlled.

60 When it is desired to begin the operation of a cask pitching machine constructed according to my invention, the kettle A and tanks B containing a greater or less quantity of cold and hard pitch, the operator 65 first opens the steam valves 16 and thereby

permits steam from the generator to pass through the loops 15 of the pipes 14. This results in softening and finally melting the pitch in the tubes 10 and the pitch contiguous to the loops 15 in the tanks B. It will 70 of course be understood that the escape cocks 12 are opened, thus providing an easy egress for any gases or vapors which may be generated from the heated pitch. The fire under the apparatus may then be started and 75 before the same shall have produced any appreciable heating effect upon the pitch in the tanks B, the steam in the loops 15 will have softened the pitch in the tubes 10 and a portion thereof in the tanks B sufficiently to prevent any injurious effects such as have been above alluded to. As soon as the pitch in the tanks B and such pitch as may be standing in the discharge pipes f has been thoroughly softened, so that an 80 escape vent through said last named pipes is provided, the escape cocks 12 are closed, and the steam valves 16 are also closed so as to shut off the steam from the loops 15.

Instead of providing loops of a steam pipe 90 extending down through relief tubes and into the pitch receptacles, as above described for the purpose of heating and softening the pitch, I may use a current of electricity, obtained from any suitable source thereof and 95 led through proper conductors, which should of course be insulated from the other parts of the apparatus in a manner which will be well understood. I consider this alternative means of heating and softening the 100 pitch in its containing receptacles as within the spirit and scope of my invention and I do not wish to limit myself to the use of steam or any one particular means of applying heat to the congealed and solidified 105 pitch.

Another feature of my present invention is providing means for heating the compressed air supply which is led into the apparatus by means of the pipes e. By reference more especially to Fig. 1, it will be seen that the main compressed air pipe e is lead into the furnace smoke discharge pipe F and forms a loop e¹. Near the lowest part of this loop e¹ may be provided a discharge cock e² by means of which any condensed moisture in the pipe e may be allowed 110 to escape. The pipe e then separates into branches e³ and e⁴, which lead to each of the tanks B and enter the same at the top, in a manner similar to that described in my former patents. A large pipe E is also provided, which passes through the apparatus back of the furnace, and is connected at one 115 end with the source of compressed air, and at the other end with the pipe e or the pipe e⁴ (the connection not being shown in the drawings.) The air on passing through this pipe E is preliminarily heated. In this case 120 it is not necessary for the air to be passed 125 130

through the loop e^1 , and the valve 17 is therefore closed.

It will be noticed that the steam pipe 14 is shown as connecting with the pipe e and 5 through that with the branch pipes e^3 and e^4 . This is in order to permit the steam to heat and melt any pitch which may have become deposited or condensed upon or in the three-way cocks 2-1 and 2-2 and which may 10 hamper the operation of the same, and also to permit hot air to be passed through the pipes 10 and loops 15, instead of steam, if preferred.

Having thus described my invention, what 15 I claim as new and desire to secure by Letters Patent is as follows:

1. The combination with a cask pitching apparatus comprising a receptacle for containing pitch and a relief device adapted to 20 permit the escape of vapor from the said receptacle; of means within the said receptacle adapted to heat and soften the pitch in said relief device so as to permit the said relief device to operate, comprising a closed loop 25 of pipe extending into the said receptacle and adapted to contain a heated fluid.

2. The combination with a cask pitching apparatus comprising a receptacle for containing pitch and a relief device adapted to 30 permit the escape of vapor from the said receptacle, said relief device comprising a tube secured to the receptacle open at the bottom and provided with removable closing means at the top; of means within the said 35 receptacle adapted to heat and soften the pitch in said relief device so as to permit the said relief device to operate, comprising a closed loop of pipe adapted to contain a heated fluid and passing down into said receptacle through said relief device.

3. The combination with a cask pitching apparatus comprising a receptacle for containing pitch and a relief device adapted to permit the escape of vapor from the said 45 receptacle, said relief device comprising a tube secured to the receptacle open at both ends but provided with means for closing the upper end when the relief device is not in operation; of means within the said receptacle 50 adapted to soften the pitch in said relief de-

vice, so as to permit the said relief device to operate, said pitch heating and softening means comprising a closed loop of pipe adapted to contain a heated fluid and passing through said relief device and down into 55 the receptacle.

4. The combination with a cask pitching apparatus comprising a receptacle for containing pitch and a relief device adapted to permit the escape of vapor from the said receptacle, said relief device comprising a tube secured to the receptacle open at both ends but provided with means for closing the upper end when the relief device is not in operation; of means within the said receptacle 60 adapted to soften the pitch in said relief device, so as to permit the said relief device to operate, said pitch heating and softening means comprising a closed loop of pipe leading from a source of heated fluid and adapted to convey said heated fluid through the said relief device and the pitch contained therein and to heat and soften said pitch.

5. The combination with a cask pitching apparatus comprising a receptacle for containing pitch and a relief device adapted to permit the escape of vapor from the said receptacle, said relief device comprising a tube secured to the receptacle open at both ends but provided with means for closing the upper end when the relief device is not in operation; of means within the said receptacle 75 adapted to soften the pitch in said relief device, so as to permit the said relief device to operate, said pitch heating and softening means comprising a closed loop of pipe leading from a source of heated fluid and adapted to convey said heated fluid through the said relief device and the pitch contained therein and to heat and soften said pitch; 80 and means for causing the heated fluid to pass through said pipe.

In witness whereof I have hereunto signed my name this 15th day of February 1908, in the presence of two subscribing witnesses.

HENRY RAUCH.
